UNITED STATES PATENT OFFICE.

WILLIAM H. CARR AND JOHN GEORGE WOLF, OF NEW YORK, N. Y.

DESIGN FOR A BELT.

SPECIFICATION forming part of Design No. 27,927, dated November 30, 1897.

Application filed August 4, 1897. Serial No. 647,127. Term of patent 3½ years.

To all whom it may concern:

Be it known that we, WILLIAM H. CARR and JOHN GEORGE WOLF, citizens of the United States, residing at New York city, in the county 5 and State of New York, have invented and produced a new and original Design for a Belt, of which the following is a specification, reference being had to the accompanying drawings, forming a part thereof, in which—

10 Figure 1 is a perspective view of a belt embodying the features of our design, and Fig. 2 is a perspective view of the belt viewed from the rear.

15 Our design relates to that class of belts which is known as "inside" belts, being adapted to be worn between the waistband of the skirt and the corset-cover or corset.

The leading feature of the design consists in a belt the central back portion A whereof is projected beyond the outer peripheral surface of the belt. 20

Another feature of the design consists in the angular slot C, which appears in the projected portion A, one member of the said slot extending to and through the upper edge of 25 the projection A of the belt.

We claim—

The design for the belt herein shown and described.

WILLIAM H. CARR.
JOHN GEORGE WOLF.
